UNITED STATES PATENT OFFICE.

EDWARD BRUNHOFF, OF CINCINNATI, OHIO, ASSIGNOR TO THE BRUNHOFF MANUFACTURING COMPANY, OF CINCINNATI, OHIO, A CORPORATION OF OHIO.

DESIGN FOR ADVERTISING AND VENDING CABINET.

Application filed August 30, 1922. Serial No. 3,596. Term of patent 7 years.

To all whom it may concern:

Be it known that I, EDWARD BRUNHOFF, a citizen of the United States of America, residing at Cincinnati, Hamilton County, State of Ohio, have invented a new, original, and ornamental Design for Advertising and Vending Cabinet, of which the following is a specification, reference being had to the accompanying drawings, forming part thereof.

The figure is a perspective view of an advertising and vending cabinet showing my new design.

I claim:

The ornamental design for advertising and vending cabinet as shown.

EDWARD BRUNHOFF.
